UNITED STATES PATENT OFFICE.

WILLIAM RALLS LEE, OF MARION, ILLINOIS.

APPARATUS FOR RECOVERING MINERALS CARRIED OFF IN THE FUMES FROM SMELTING-FURNACES.

SPECIFICATION forming part of Letters Patent No. 704,199, dated July 8, 1902.

Application filed August 28, 1901. Serial No. 73,613. (No model.)

To all whom it may concern:

Be it known that I, WILLIAM RALLS LEE, a citizen of the United States, residing at Marion, in the county of Williamson and State of Illinois, have invented a new and useful Apparatus for Recovering Minerals Carried Off in the Fumes from a Smelting-Furnace, of which the following is a specification.

My invention is an improved apparatus for recovering minerals carried off in the fumes from a smelting-furnace; and it consists in the peculiar construction and combination of devices hereinafter fully set forth and claimed.

In the accompanying drawings, Figure 1 is a perspective view, partly in section, of an apparatus embodying my improvements, showing the same connected to a smelting-furnace. Fig. 2 is a detail transverse sectional view of my improved apparatus.

In the embodiment of my invention I provide a precipitating-chamber 1, which is here shown ashizontally disposed and as being oblong in form. In practice this precipitating-chamber may be of any suitable size and constructed of any suitable material. The bottom 2 of the said precipitating-chamber is inclined laterally to shed water, and at the lower side of the inclined bottom is a trough 3, which leads from one end of the said precipitating-chamber. The latter is divided into a series of compartments 4 by baffle-plates 5 6, which are associated in pairs, the baffles 5 depending from the top of the precipitating-chamber and the baffles 6 projecting vertically from the bottom thereof, said baffles 5 6 being suitably spaced apart, and hence the precipitating-chamber forms, in effect, a continuous tortuous passage. At the rear end of the said precipitating-chamber an eduction-flue 7 leads therefrom, and in the said eduction-flue is a suction-fan 8.

A smoke-flue 9 leads from the smelting-furnace A. The said smelting-furnace may be of any suitable construction. That portion of the flue which leads immediately from the furnace forms an uptake 10, said flue being curved at 11 and formed with a downtake 12. The latter discharges into the precipitating-chamber at the front end thereof, so that the smoke, fumes, products of combustion, and the minerals carried by the fumes from the furnace will be discharged into said

precipitating-chamber and caused to pass therethrough from its front end to its rear end by the blast through the eduction-flue 7 55 and the exhaust-draft created by the fan 8 through the said precipitating-chamber. It will be understood that the baffles cause the fumes and the minerals carried thereby to descend successively in the chambers 4 and 60 to pass from one chamber to another through the uptakes formed by the spaces between the baffles 5 6. A steam-pipe 13, which leads from a suitable boiler, (not shown,) is provided with a nozzle which discharges a jet 65 of steam upwardly in the uptake 10 of flue 9 at the point where said uptake leads from the furnace. This steam-jet accelerates the draft, promotes combustion of the combustible substances in the fumes, and moistens the 70 mineral particles carried by the fumes. A water-pipe 14, which leads from a suitable source of water, is provided with a nozzle which discharges spray downwardly in the downtake 12 of flue 9, said nozzle being indicated by the reference-numeral 15. Nozzles 16 depend from the said pipe 14 and spray water downwardly in the chamber-compartments 4. Hence the fumes which pass from the furnace through the precipitating-chamber are showered with 75 water during their descent through the downtake 12 and during their passage through the various compartments 4, the effect of the water thus showered downwardly on the fumes being to condense the particles, including the 80 minerals, and precipitate them to the bottom of the precipitating-chamber. The extent of the precipitating-chamber in practice is such that when the fumes have passed through all the various compartments thereof the minerals carried by the fumes have been separated 85 90 therefrom and precipitated to the bottom of the said chamber. The minerals carried off by the water descending on the bottom of the precipitating-chamber to the trough 95 3 are discharged from the latter at one end of the precipitating-chamber. I also employ a series of settling-troughs 17, of which any suitable number may be employed, which settling-troughs are provided with baffles or 100 riffles 18. A pipe 19 leads from the trough 3 and is connected by branches 20 to the settling-troughs. As here shown there are two of the said troughs and two of the said

branches, and I provide the pipe 19 with a valve 21, by which water carrying the minerals separated from the fumes and precipitated in the chamber 1 may be caused to flow to either of the settling-troughs at will. The minerals settle in the said troughs, the water flowing therefrom through spouts 22. While the minerals are being recovered from one of said settling-troughs the other may be in operation.

By means of my improved apparatus the minerals which are ordinarily wasted by being carried off in the fumes of a smelting-furnace and discharged in the outer air may be readily recovered. Furthermore, by my improved apparatus the noxious properties of the smelter-fumes are destroyed.

It will be understood that in practice the precipitating-chamber is provided with doors, which may be opened to permit the removal of mineral therefrom.

Having thus described my invention, I claim—

1. The combination with a smelting-furnace, of a precipitating-chamber having baffle-plates arranged therein and separating the chamber into communicating compartments, an induction-flue connecting one end of the chamber with the furnace and including

means for accelerating the projection of fumes to the chamber and for moistening the same, water-spraying mechanism arranged in the compartments, an eduction-flue including suction mechanism connecting with the other end of the chamber, a conduit for conveying the precipitated materials from the chamber, and settling-troughs including valve mechanism connecting with the conduit.

2. The combination with a smelting-furnace, of a precipitating-chamber, an inverted-U-shaped flue connecting one end of the chamber with the dome of the furnace, an upwardly-discharging steam-pipe entering the leg of the flue connecting with the furnace, a downwardly-discharging water-pipe connecting with the leg of the flue entering the chamber, water-spraying means communicating with the chamber, and a flue including suction mechanism disposed at the discharge end of the chamber.

In testimony that I claim the foregoing as my own I have hereto affixed my signature in the presence of two witnesses.

WILLIAM RALLS LEE.
